UNITED STATES PATENT OFFICE

149,658

DESIGN FOR A LOUNGE CHAIR

Frank J. Luketa, Seattle, Wash.

Application August 26, 1946, Serial No. 132,845

Term of patent 14 years

(Cl. D15—1)

To all whom it may concern:

Be it known that I, Frank J. Luketa, a citizen of the United States of America, residing at Seattle, in the county of King and State of Washington, have invented a new, original, and ornamental Design for a Lounge Chair, of which the following is a specification, reference being had to the accompanying drawing, forming part thereof.

Figure 1 is an isometric view of a lounge chair, with the leg rest thereof projected forwardly, showing my new design.

a lounge chair, with parts in the position occupied in Figure 2, both Figure 2 and Figure 3 showing my new design.

I claim:

The ornamental design for a lounge chair, substantially as shown and described.

FRANK J. LUKETA.
